MANIFOLDING DEVICE

Arthur A. Johnson, Bridgeport, Conn., assignor
to Autographic Register Company, Hoboken,
N. J., a corporation of New Jersey

Application March 16, 1936, Serial No. 69,047

27 Claims. (Cl. 282—21)

This invention relates to manifolding registers, of the type including a platen over which a plurality of record strips can be advanced form-length amounts at each operation of a feeding means including upper and lower strip-engaging members customarily located intermediate the ends of the casing.

The general object of the invention is to provide a register wherein the top of the register can be made flat, and at the same time the platen can be in an ideal writing position, for instance, horizontal and close to the top of the register.

A permanently upstanding hood to cover and protect the overlying member of the feeding means, although heretofore deemed essential, is disadvantageous for many reasons, not the least of which is that it is detrimental to storage and packaging and shipping.

Giving the feeding means a fixed location in the casing, and also a fixation of the platen in writing position once a strip passing over the same is engaged with the feeding means, have heretofore been considered essential features of an autographic register.

The present invention involves the broad concept that relative fixation between an appointed location for the feeding means, and an appointed location for the platen all the while a strip is threaded through the register for advancement by the feeding means, is not necessary in order to provide a satisfactory operating autographic register. Conversely, the present invention contemplates that the platen and the feeding means can be relatively movable, whether it be the feeding means which is moved relative to the platen, or vice versa, while a strip is threaded through the register for advancement by the feeding means. In either case such a relative movement would be effected preparatory to a strip advancement, and it would be so effected that the relative disposition of the platen and the feeding means is varied to one such that a strip in passing over the platen while being advanced by the feeding means would be thus advanced while the platen is in strip-feeding relation to the feeding means, whether the platen be ahead of or beyond the feeding means in the direction of strip advancement. If it is the feeding means which is moved relative to the platen, such means would be elevated, and during its period of elevation, that is, during the period allotted for strip advancement, the protective hooding structure over the presser roller would be elevated above the top of the casing. But on lowering the feeding means after the strip ad-

vancement, which would set the register to allow a set of forms then at rest on the platen or thereafter brought to rest thereon to be inscribed, the top of the casing would again be made flat, provided said hooding structure was so formed, 5 as it could well be, to bring about this result.

One of the objects of the invention is also to provide means operable from the exterior of the casing, and other than a part of or on the platen exposed through the writing opening, for shifting the movable platen back and forth between its two positions.

Another object is to provide, in combination with the means last referred to, means for holding the platen in its elevated or writing position 15 while a set of forms is being inscribed and for holding the platen in its lowered position, which latter may be termed its feeding position, during a strip-advancing operation of the feeding means.

According to one now preferred way of carrying out the invention, the platen is the shifted part and a platen-shifting means is provided which operates to shift the platen from one of its appointed positions to the other thereof while operatively associated with strip-feed-controlling means incorporating not only strip-advancing means in the shape of roller and feed disks or equivalents but also two coadjuvants familiar in the art, to wit, a means for locking the strip-advancing means at the conclusion of each strip-advancing operation, and a manually operable means for releasing this locking means to free the strip-advancing means for another strip-advancing operation.

The operative connection referred to is preferably one such that manual operation of an actuator at the exterior of the casing for releasing said locking means, such actuator generally termed a starter, results in shifting the platen from feeding to writing position, to allow a set of forms to be inscribed while on the platen with the latter in writing position; and also one such that the platen is shifted again to feeding position incidental to initiation of operation of the strip-advancing means by manual operation of another actuator, as the commonly employed strip-feeding crank, at the exterior of the casing.

According to another now preferred way of carrying out the invention, also wherein the platen is the shifted part, the platen is also maintained in one position all the time the machine is idle. But in this case the platen is so maintained in writing position, instead of in feeding position, as in the case last 55

discussed, while the machine is idle. Here, too, a platen-shifting means can be operatively associated with the strip-feed-controlling means, and such operative connection can be associated with the strip-advancing means of said strip-feed-controlling means and also with the releasing means for the latter.

Other features and advantages will hereinafter appear.

10 10 In the accompanying drawings which illustrate preferred forms of the invention wherein the writing platen is moved relative to the feeding means from a writing position to a different feeding position, and vice versa:

15 15 Figure 1 is a top plan view of a register according to the invention and having a platen so movable.

Fig. 2 shows said register partially in side elevation and partially in longitudinal section.

20 20 Fig. 3 is an enlarged partially broken away detail plan view, showing the platen and a strip-feed-controlling means operatively connected thereto, with, however, the presser roller omitted for clarification.

25 25 Fig. 4 is a longitudinal sectional view, showing the platen in feeding position and all the parts of Fig. 3 as they become disposed at the conclusion of a strip advancement and as they remain while the machine is idle; the strip-advancing means included in the strip-feed-controlling

30 30 means comprising a presser roller and feed disks now locked against a strip-advancing operation.

Fig. 5 is a view similar to Fig. 4, showing the platen in writing position as the result of manually operating a releasing means for the lock last-mentioned, so that now a set of forms on the platen can be inscribed for subsequent advancement.

35 35 Fig. 6 is also a view similar to Fig. 4, but showing the strip-advancing means being operated with the platen again lowered to feeding position.

40 40 Fig. 7 is a view similar to Fig. 5, but showing the register of Figure 1 equipped with another preferred form of platen-shift-controlling means and one wherein the platen is in an elevated writing position all the while the machine is idle.

45 45 Fig. 8 shows the parts of Figure 1 as disposed when the platen is lowered during strip-advancing operation of the strip-advancing means.

50 50 Referring particularly to the exemplifying form of the invention illustrated in Figures 1 to 6, a register is shown conventionally as including a casing 15 having a plane bottom wall and plane end and side walls, and closed over when set for operation by a top including a top

55 55 subdivision 16 carrying a writing opening 17 and hinged to the casing at 18. As this register is shown, it is provided with a supply compartment 19 for receiving the record strips; these strips being shown as stored in compartment 19 as a zigzag folded stack or pile 20, wherein the strips

60 60 are so interfolded at form-length intervals that extended between each two successive lines of fold, corresponding to the one indicated at 21, are a set of forms successive ones of which are to be brought to writing position on a platen 22 and after being there inscribed are further to be advanced to pass beyond the platen on each operation of a strip-advancing means including

65 65 a presser roller 23 and a pair of feed disks 24; these disks 24 being fixed on a shaft 25 extending across the casing and carrying a spur gear 26 for meshing with a familiar spur pinion not shown but fixed on a shaft 27 on which the presser roller 23 is fast. Thus on turning a crank 28

70 70 the strip-advancing means can be operated, that is, the presser roller and the feed disks can be rotated through a complete revolution of the latter to advance the strips a form-length amount through the zone of bite on the strips between the presser roller and the feed disks. Such bite in the case illustrated is a true bite and merely a frictional one; but for convenience this term is used herein broadly to designate any bite or equivalent feeding engagement of the record strips between overlying and underlying feeding elements for the record strips, as, for instance, that obtained when a so-called pin-wheel feed is employed. Strip-arresting form-registering apertures or equivalents not shown are assumed to be carried by the strips at form-length intervals therealong; to cooperate with the strip-feeding means illustrated, and in a well known manner according to which strip advancement is arrested to halt a follower set of forms on the platen for the addition of writing to such forms when said apertures enter the points of bite between the presser roller and the feed disk. Hence, the feed disks 24 are here shown as carrying starter shoes 29, which during an earlier part of the 25 revolution of the disks cooperate with the latter to engage solid portions of the strips beyond said apertures to advance the strips sufficiently to move the apertures beyond the points of said point of bite. The strip-advancing means just 30 described is here shown as located intermediate the ends of the casing, although it need not be so located in carrying out the present invention; and the platen is here shown as located ahead of said advancing means, although it need 35 not be so located in carrying out the present invention. With these instrumentalities arranged as illustrated, it is convenient to provide a receiving compartment 30 forward of the advancing means, into which compartment the forms 40 of the lowermost record strips are to be received and collected as indicated at 31, as one set of forms after another on a plurality of record strips, after being brought to rest on the platen and there inscribed, are moved by the strip-advancing 45 means to transport the forms of said set on the upper strips to tear-off location; the underlying record strips being assisted in their passage into the receiving compartment 30 by a roller 32 rotated by a pinion 33 meshing with gear 26. 50 This compartment 30 is covered in part by a fixed top subdivision 34, and in part by a door 35 hinged at 36.

The parts so far described are according to standard and approved practices in the art. 55

Referring now to the parts of Figures 1 to 6 which illustrate the features of the present invention in the exemplifying form embodied therein showing these views, it will be noted that the casing top is shown as including a top subdivision overlying the strip-advancing means which is flush with the top subdivision beyond said means and with the top subdivision ahead of such means. In the present case, the top subdivision last-mentioned and also the top subdivision over the strip-advancing means are shown as parts of the top subdivision 16 carrying the writing opening 17 and hinged to the casing at 18; this top subdivision 16 including beyond the roller 23 a depending wall 37 completely hooding said roller and properly locating a tear-off or knife 38 for severing the upper forms of a set of forms on arrival at tear-off location as the result of said upper forms being directed upwardly by an 75

inclined deflector wall 39 carried by the top subdivision 34.

While a plurality of strips are being placed in the storage compartment and threaded through the register over the platen 22 and into engagement with the strip-advancing means, the top subdivision 16 is raised. But, all the while the register is operable following such a threading, the casing has its characteristic flat top.

This flat top casing is made possible by lowering the strip-advancing means so that the presser roller is below said top. Here the flat casing top is permanently flat all the while the machine is operable for strip advancement because the strip-advancing means is given a fixed location. However, relative movement between said means and the platen is provided for, here by pivotally mounting the platen as at 40. This pivotal mounting of the platen is such that it can be elevated as in Fig. 5, to writing position, or lowered as in Fig. 4, to feeding position. When feeding position of the platen, or a strip-feeding relation between the platen and the strip-advancing means, is referred to herein there is meant broadly a different position than the writing position of the platen, or a different relation between the platen and the feeding means than the relation of these parts when a set of forms on the platen is to be inscribed, and one wherein the platen is made more facilitative of efficient and dependable strip advancement or one only wherein practicable strip advancement is permitted.

The means for moving the platen from one position to the other and vice versa is here inclusive of operating means exterior to the casing, to wit, the crank 28, and a so-called starter or actuator for a releasing means for a locking means which becomes effective at the conclusion of each strip advancement by locking the feed disks at the conclusion of each revolution thereof.

Said starter is here shown as including an actuator in the form of a finger piece 41 at the exterior of the casing on a rock shaft 41a extending transversely of the casing and rotated when said finger piece is pressed down to swing an arm 42 upwardly in order to release the feed disk locking means; this arm at its free end carrying a claw 43 which with a stud 44 offset from a plate 45 fixed on shaft 25 forms the locking means for the feed disks 24. Said arm 42 is loose on the rock shaft 41a, but is moved upwardly as just described by the engagement of a finger 46 fixed on said rock shaft 41a with a pin 47 on the arm 42.

In order to cause the operation of such a starter to elevate the platen 22 to writing position, the following parts are provided. Fast on a rock shaft 48 is an upstanding arm 49, under some restraint because of a light retractile coil spring 49a, and shaped at its top or free end to present a ledge-receptor or keeper 50 for one end of a rod 51 extended between a pair of arms 52 fixed on rock shaft 41a.

This rod 51 is out of its keeper 50, and the parts are arranged as shown in Fig. 4, following the conclusion of a strip advancement and before the finger piece 41 is depressed. Then the platen is inclined downwardly toward the bite of the strip-advancing means so as to be in strip-feeding position; the platen dropping to this position by its own weight and being retained in this position by support of its under surface on rod 51.

When, however, the finger piece is depressed to release the claw 43 from the stud 44, this freeing the feed disks 24 for rotation by the crank 28, the platen elevating rod 51 is raised and entered in its keeper 50 thereby throwing the platen to writing position as shown in Fig. 5 and holding it in that position so that a set of forms thereon can be inscribed while horizontally supported at the top of the casing. While the platen is thus held elevated the finger 46 holds the claw 43 above and out of engagement with the pin 44.

In order to cause subsequent turning of the crank 28 to lower the platen to feeding position and then to allow the claw 43 to drop, the following parts are provided. Fixed on the same rock shaft 48 which carries the arm 49 is a trip finger 53 and on the plate 45 is a projection in the shape of a stud 54 for tripping said finger. On first turning the crank 28 to rotate the said disks 24 in the direction of the arrow shown in Fig. 6, stud 54 engages the trip finger 53, as shown in Fig. 5, and on further turning the crank this stud rocks the arm 49 sufficiently in a clockwise direction against the spring 49a to free the rod 51 from its keeper 50 at the top of arm 49 and to allow said rod to descend along the convexly curved face 49' of said arm. Thereupon, the platen drops to its feeding position, and the parts become disposed as in Fig. 6. Note that the claw is now also dropped. They remain so disposed until one revolution of the feed disks 24 is completed, whereupon they become disposed as in Fig. 4, where the locking means for the feed disks becomes effective by engagement of the claw 43 with the stud 44. The platen, it will be noted, remains in its feeding position.

The operation of the embodiment of the invention just described is briefly summarized as follows:

With the strips engaged with the strip-advancing means comprising roller 23 and feed disks 34 as shown in Fig. 2, the register is ready for operation as and when desired, and during all this period of operability the top of the casing is permanently maintained flat and the platen remains lowered in feeding position. The strip-advancing means is now locked at 43-44 as shown in Fig. 3.

Whenever it is desired to inscribe a set of forms on the platen and advance such set to send the form of the lowermost strip to the receiving compartment 30 and the forms on the overlying strips to the tear-off location, the finger piece 41 is depressed to release the lock for the disks 24, thus bringing the parts 43 and 44 to the relation shown in Fig. 5. Coincidentally with such release, the platen is lifted to writing position and there held by the detent means 50-51, as also shown in Fig. 5.

When the desired writing has been performed on the forms now on the elevated platen, the operator merely starts turning the crank 28 to rotate the feed disks 24 in the direction of the arrow shown in Fig. 6.

The first thing that happens is the stud 54 arrives at the position marked 54a in Fig. 6 and releases the detent means 50-51 so that the platen drops to feeding position. Simultaneously, the claw 43 also drops as shown in Fig. 6, to reestablish the lock 43-44. The starter shoes 79 are so placed on the disks 24 that strip advancement is deferred until the platen has first dropped to feeding position. Following such dropping of the platen, however, said shoes initiate strip advancement and restore solid portions 70

on the strips to the points of bite between the roller 23 and disks 24.

As the parts are shown in Fig. 6, the stud 54 has arrived at a location 54b, and the strips are now being advanced a form-length by conjoint action of the roller and feed disks.

When the feed disks have completed a full revolution, by which time the strips have been advanced a form-length amount, the pin 44 again 10 is engaged by the claw 43 to lock the disks against another revolution until the finger piece 41 has again been depressed.

An advantage of the embodiment of the present invention such as above described, wherein 15 the platen is moved back and forth between writing and feeding positions, and wherein the platen remains in feeding position all the while the machine is idle, is that the path of travel of the strips from the delivery end of the strip to the 20 strip-advancing means is changed in direction only while the platen is elevated for the short period of time required to inscribe a set of forms, and therefore any chance whatever of imparting even a slight curling tendency to a set of forms 25 is avoided.

Referring now particularly to the exemplifying form of the invention illustrated in Figs. 7 and 8, the parts numbered 16, 17, 19, 22, 23, 24, 25, 27, 28, 29 and 60 in these views correspond, intrinsically and relative to coaction with each other, 30 to the similarly numbered parts in Figures 1 to 6. Thus, here also the flat top casing is made possible by lowering the strip-advancing means so that the presser roller 23 is below said top, and 35 here also the flat casing top is permanently flat all the while the machine is operable for strip advancement because the strip-advancing means is given a fixed location. In other words, relative movement between said means and the platen 22 is here also provided for by pivotally mounting 40 the platen.

The means for moving the platen from one position to the other and vice versa is also here inclusive of operating means exterior to the casing, to wit, the crank 28, and a starter. This 45 starter as shown includes a finger piece 60.

The platen moving means shown in Figs. 7 and 8 includes a circular plate 61 at one side of the register and fixed on the shaft 25 which carries the feed disks 24. Said plate is mutilated to 50 provide a recess 62 carrying what may be termed a cam portion 63. The diameter of the plate 61 is less than that of the feed disks 24, to keep the plate always out of contact with a strip (not shown) while the same is being fed through the 55 machine. Finger piece 60, at the exterior of the casing, is on the free end of an arm 64 fixed on a rock shaft 65 extending across the machine and having alignedly fixed thereon, below opposite sides of the platen, the lower links 66 of a pair 60 of toggles, the upper links 67 of which toggles are pivotally connected to the underside of the platen at 67. The upper and lower links of each toggle are pivotally interconnected by being loosely sleeved about a transverse rod 69 joining 65 the toggles and establishing a sturdy toggle frame. A dog 70 is also loose on said rod 69, and rockable thereon in the plane of the plate 61, within the limits allowed by coaction between a pin 71 on the seen toggle link 66 and a fork 72 70 carried by dog 70. The link 66 last referred to has a depending extension 73 for coaction with a fixed stop 74; the toggle frame being urged to the condition shown in Fig. 7 to cause said extension to abut said stop, by a retractile spring 75.

Operation

After a full revolution of the feeding disks 24 by turning of the handle 28 for advancing the record strips a form-length amount, the parts, then brought to the condition shown in Fig. 7, 5 remain in that position all the while the machine thereafter remains idle. Now the toggles are thrown slightly to the left beyond dead center, and cannot further collapse in that direction due to engagement of the extension 73 with the stop 74. Thus a set of strip-carried forms now on the platen is firmly supported by the platen immediately below the writing opening 17. At the same time, the feed disks are locked 10 against rotation by the engagement of the dog 70 15 with the recess 62.

After the forms have been inscribed, a depression of the finger piece 60 drops the platen to feeding position by collapsing the toggle toward 20 the right, as shown in Fig. 8. This withdraws the dog 70 from the recess 62, and as soon as such withdrawal is completed the dog drops by its own weight to the position shown in Fig. 8. The degree of such drop, however, is limited to that 25 shown in Fig. 8 by the pin and fork connection 71—72.

Now the crank 28 can be turned to rotate the disks 24 in the direction shown by the arrow in Fig. 8; the starter shoes 29 first coacting with 30 the roller 23 to grip and advance the strips until they can be advanced at the bite between said roller and the feed disks, and thereafter, during the completion of a full revolution by said disks, the strips are advanced by the disks and the roller the balance of a form-length-amount. The working peripheries of the feed disks are such that during the concluding part of a revolution thereof, and after the completion of strip advancement, that part of the mouth of the recess 62 adjacent to the wall 62a thereof arrives 35 opposite the dog 70 and the dog is reinserted in the recess by the spring 75. During a further rotation of the disks, the cam portion 63 of the recess acts on the dog to rearrange the toggles as shown in Fig. 7, and, just as the feed disks 40 complete their revolution, to restore the platen to writing position and to lock the feed disks 45 against further rotation.

An advantage of an embodiment of the invention such as just above described, wherein the platen is moved back and forth between writing and feeding positions and wherein the platen remains in writing position all the while the machine is idle, is that the platen closes the top of the machine at the writing opening at all times 55 except when the platen is lowered for a strip advancement operation by the feeding means.

Variations and modifications may be made within the scope of this invention and portions 60 of the improvements may be used without others.

I claim:

1. In a manifolding register, record strip feeding means including underlying and overlying strip-engaging members; a platen over which a strip extends while in engagement with the feeding means; a casing enclosing the feeding means and the platen and having a top below the general plane of which said overlying member is wholly located, the platen and the feeding means being relatively movable within the casing; and means for effecting a relative movement between the feeding means and the platen to vary the inclination of a strip-guiding surface of the platen relative to a horizontal plane containing the bite 65 of the two members of the feeding means.

2. The register defined in claim 1, wherein the same includes strip-feed-controlling means, a part of which is constituted by said strip-feeding means, and there is provided an operative connection between said strip-feed-controlling means and said means for effecting a relative movement between the strip-feeding means and the platen, whereby predeterminedly during operation of said strip-feed-controlling means said 10 movement-effecting means is operated.

3. The register defined in claim 1, wherein the same includes means for locking said strip-feeding means; means for releasing said locking means; and an operative connection between 15 said releasing means and said means for effecting a relative movement between the strip-feeding means and the platen whereby manual operation of one of the two means last-mentioned causes operation of the other.

20 4. In a manifolding register, the combination of a casing; record strip feeding means therein including overlying and underlying strip-engaging members establishing a strip-advancing bite therebetween, said overlying member being wholly below the casing; a platen over which a strip is advanced by operation of the feeding means and movably mounted for varying the approach of the strip toward said bite; and means for moving the platen to vary such approach by downward inclination thereof toward said bite and operable only while the feeding means is idle relative to strip advancement.

25 5. In a manifolding register, the combination of a casing; record strip feeding means therein including overlying and underlying strip-engaging members establishing a strip-advancing bite therebetween, said overlying member being wholly below the casing; a platen over which a strip is advanced by operation of the feeding means and movably mounted for varying the approach of the strip toward said bite; means for moving the platen toward and away from a position for bettering such approach for strip advancement by said members; and means for precluding either such operation of said moving means except when the feeding means is idle relative to strip advancement.

30 6. In a manifolding register, the combination of manually operable means for allowing and effecting the advancement of a record strip through the register over a form-length extent, said means including as a strip-advance-effecting means overlying and underlying strip-engaging members; a casing in which said members are located to dispose the overlying member wholly below the general plane of the top of the casing; a platen near such casing top over which a strip is advanced by operation of the feeding means and movable within the casing for varying the feeding of the strip toward said bite; and means for thus moving the platen operable in timed relation with the means first-mentioned.

35 7. In a manifolding register, the combination of record strip feeding means including underlying and overlying strip-engaging members; a casing in which said feeding means is housed with said overlying member wholly below the general plane of the top of the casing; a platen over which a strip is advanced by operation of the feeding means, said platen being movable in the casing from an elevated writing position to a less elevated position wherein the platen better guides a strip toward the strip-engaging bite between said members, and vice versa; and

means operatively connected to the feeding means for moving the platen to its last-mentioned position incidental to the starting of a feeding operation and for moving the platen to its first-mentioned position incidental to the 5 conclusion of a feeding operation.

8. In a manifolding register, the combination of record strip feeding means including underlying and overlying strip-engaging members; a casing in which said feeding means is housed with said overlying member wholly below the general plane of the top of the casing; means for setting the feeding means for a strip-advancing operation; a platen over which a strip is advanced during operation of the feeding means, said platen pivotally mounted in the casing and swingable back and forth between an elevated writing position and an inclined position wherein the platen better guides a strip toward the strip-engaging bite between said members; and means operatively 10 connected to one of the setting and feeding means for automatically insuring that the platen is in its said inclined position before the start of a strip-feeding operation.

15 9. In a manifolding register, a pivotally mounted platen; feeding means for advancing a strip over said platen and including annular members between the bite of which said strip is engaged during advancement thereof; a casing below the general plane of the top of which said overlying member is wholly located; means for holding the platen in a writing position with its strip-delivery end above said bite between successive operations of the feeding means; and means operable preliminary to advancement of 30 a strip by the feeding means for rocking the platen downwardly on its pivot to lower said end to dispose the platen in another position than the writing position and one more facilitative of strip advancement by the feeding means. 35

10. In a manifolding register, strip-advancing means including overlying and underlying members having a strip-engaging bite; and a platen movable back and forth between an upper writing position and a different and lower position 45 wherein a strip thereon is directed to enter said bite substantially tangentially.

11. In a manifolding register, a casing; strip-feeding means including underlying and overlying rotary strip-engaging members, said overlying member being located wholly below the general plane of the top of the casing; rotating means therefor including a manually operated actuator; latch means for halting rotation of said members at the conclusion of the strip-feeding operation; a manually operable releasing means for said latch; a pivotally mounted platen, said casing having a writing opening above the platen, the strip-engaging bite of said rotary members being below said opening; means 50 for rocking the platen to move upwardly to move the same toward said opening on operation of the starting means; and means for rocking the platen downwardly to direct the same toward said bite during operation of said actuator. 55

12. In a manifolding register, the combination of record strip feeding means including overlying and underlying annular strip-engaging members; a casing in which the feeding means is placed to position the overlying one of said 70 members below the general plane of the top of the casing; a platen over which a strip is advanced by operation of the feeding means; means mounting the platen for movement toward and away from the top of the casing for varying 75

- the direction of approach of a strip toward the bite between the feeding members while such strip is on the platen and extended between said members, whereby when the platen is at the 5 end of its movement toward the top of the casing the platen is in a good writing position and when the platen is at the end of its movement away from the top of the casing the platen is a good strip-advancing position, and means operable from the exterior of the casing for thus 10 moving the platen.
13. In a manifolding register, strip-advancing means; a platen over which a strip is extended while in engagement with the advancing means; means for effecting a relative movement between the advancing means and the platen to vary the relation of the platen to the advancing means in regard to directing the strip in more efficient or less efficient feeding direction relative to the 15 advancing means; means for setting the advancing means for strip advancement; and means operating in timed relation with the setting means to vary the relation of the platen to the advancing means.
14. In a manifolding register, the combination of record strip feeding means including overlying and underlying strip-engaging members; a casing in which the feeding means is placed to position the strip-engaging bite of said members below the general plane of the top of the 20 casing; a platen over which a strip is advanced by operation of the feeding means; means mounting the platen for movement within the casing for varying the direction of approach toward said bite of a strip while such strip is on the platen and extended between said members; means for thus moving the platen; and means for operating the means last-mentioned rendered operative by operation of the feeding means.
15. In a manifolding register, the combination of record strip feeding means including overlying and underlying strip-engaging members; a casing in which the feeding means is placed to position the strip-engaging bite of said members below the general plane of the top of the casing; a platen over which a strip is advanced by operation of the feeding means; means mounting the platen for movement within the casing for varying the direction of approach toward said bite of a strip while such strip is on the platen and extended between said members; means for thus moving the platen; and means for operating the means last-mentioned held inoperative during operation of the feeding means while strip advancement is being effected thereby.
16. In a manifolding register, the combination of record strip feeding means including overlying and underlying strip-engaging members; a casing in which the feeding means is placed to position the strip-engaging bite of said members below the general plane of the top of the casing; a platen over which a strip is advanced by operation of the feeding means; means mounting the platen for movement within the casing for varying the direction of approach toward said bite of a strip while such strip is on the platen and extended between said members; means for thus moving the platen; means for holding the feeding means inoperative for strip advancement after a previous strip advancement and including means for holding the platen-moving means inoperative; and means for releasing the feeding means for a subsequent strip advancement and including means for operating the platen-moving means.
17. In a manifolding register, the combination of record strip feeding means including overlying and underlying strip-engaging members; a casing in which the feeding means is placed to position the strip-engaging bite of said members below the general plane of the top of the casing; a platen over which a strip is advanced by operation of the feeding means; means mounting the platen for movement within the casing for varying the direction of approach toward said bite of a strip while such strip is on the platen and extended between said members; means for thus moving the platen; means for holding the feeding means inoperative for strip advancement after a previous strip advancement and including means for holding the platen-moving means inoperative; and means for releasing the feeding means for a subsequent strip advancement and including means whereby the platen-moving means may be operated.
18. In a manifolding register, the combination of record strip feeding means including overlying and underlying strip-engaging members; a casing in which the feeding means is placed to position the strip-engaging bite of said members below the general plane of the top of the casing; a platen over which a strip is advanced by operation of the feeding means; means mounting the platen for movement within the casing for varying the direction of approach toward said bite of a strip while such strip is on the platen and extended between said members; means for thus moving the platen; means for holding the feeding means inoperative for strip advancement after a previous strip advancement and including means for holding the platen-moving means inoperative; and means for releasing the feeding means for a subsequent strip advancement and including means whereby the platen-moving means may be operated.
19. In a manifolding register, the combination of record strip feeding means including overlying and underlying strip-engaging members; a casing in which the feeding means is placed to position the strip-engaging bite of said members below the general plane of the top of the casing; a platen over which a strip is advanced by operation of the feeding means; means mounting the platen for upward inclination toward a substantially horizontal writing position and operable only while the feeding means is idle relative to strip advancement.
20. In a manifolding register, the combination of strip-feed-controlling means including strip-advancing means incorporating overlying and underlying strip-engaging members; a casing in which said members are located to dispose the strip-engaging bite thereof below the general plane of the top of the casing; a platen near such casing top over which a strip is advanced by operation of the feeding means and movable within the casing for varying the feeding of the strip toward said bite; and means for thus moving the platen automatically operated during operation of the means first-mentioned.
21. In a manifolding register, the combination of record strip feeding means including underlying and overlying strip-engaging members; a casing in which said feeding means is housed; a platen near the top of the casing and over which a strip is advanced by operation of the feeding means, said platen being movable in the casing from an elevated writing position to a less elevated position wherein the platen better guides

a strip toward the strip-engaging bite between said members, and vice versa; strip-feed-halting means operable to release said feeding means; and means operably connected to said halting 5 means for moving the platen to its less elevated position.

22. In a manifolding register, the combination of record strip feeding means including underlying and overlying strip-engaging members; a casing 10 in which said feeding means is housed; a platen near the top of the casing and over which a strip is advanced by operation of the feeding means, said platen being movable in the casing from an elevated writing position to a less ele- 15 vated position wherein the platen better guides a strip toward the strip-engaging bite between said members, and vice versa; strip-feed-halting means operable to release said feeding means; means operably connected to said halting means 20 for moving the platen to its less elevated position; and means operated by the feeding means for moving the platen to its said writing position.

23. In a manifolding register, the combination of record strip feeding means adapted at each 25 operation thereof to advance a strip a form-length amount; a platen over which a strip is advanced by operation of the feeding means and mounted for movement from a more efficient to a less effi- 30 cient position relative to strip feeding and vice versa; and means operatively connected to the feeding means for moving the platen to its more efficient position incidental to the starting of a feeding operation.

24. In a manifolding register, the combination 35 of record strip feeding means adapted at each operation thereof to advance a strip a form-length amount; a platen over which a strip is advanced by operation of the feeding means and mounted for movement from a more efficient to a less effi- 40 cient position relative to strip feeding and vice versa; and means operatively connected to the feeding means for moving the platen to its more efficient position incidental to the starting of a feeding operation and for moving the platen to 45 its less efficient position incidental to the conclusion of a feeding operation.

25. In a manifolding register, the combination of record strip feeding means adapted at each operation thereof to advance a strip a form-length amount; a platen over which a strip is advanced by operation of the feeding means and mounted 5 for movement from a more efficient to a less effi- 10 cient position relative to strip feeding and vice versa; means operatively connected to the feeding means for moving the platen to its more efficient position incidental to the starting of a feeding 15 operation and for moving the platen to its less efficient position; and means for moving the platen only while the feeding means is idle for strip advancement between successive strip ad- 15 vancements.

26. In a manifolding register, the combination of record strip feeding means including underlying and overlying strip-engaging members; a casing 20 in which said feeding means is housed; means for setting the feeding means for a strip-ad- 25 vancing operation; a platen over which a strip is advanced during operation of the feeding means, said platen pivotally mounted in the casing and swingable back and forth between an elevated writing position and an inclined position wherein 30 the platen better guides a strip toward the strip- 35 engaging bite between said members; and means operatively connected to one of the setting and feeding means for moving the platen to its last-mentioned position and insuring such movement before the start of a strip-feeding operation.

27. In a manifolding register, a casing; a platen mounted therein and adapted to be positively moved alternately upwardly to and downwardly from a writing position, the casing having a top 35 carrying a writing opening over the platen; strip-advancing means and starter means therefor; and means controlled by both the means last mentioned for moving the platen back and forth between said writing position and another and 40 lower position which is more efficient for strip guidance during strip advancement than the writing position.

ARTHUR A. JOHNSON. 45
